UNITED STATES PATENT OFFICE.

GEORGE W. SMITH, OF DALLAS, TEXAS.

FLEXIBLE BRACE.

1,317,330.

Specification of Letters Patent. Patented Sept. 30, 1919.

Application filed August 9, 1918. Serial No. 249,126.

To all whom it may concern:

Be it known that I, GEORGE W. SMITH, a citizen of the United States of America, residing at Dallas, in the county of Dallas 5 and State of Texas, have invented new and useful Improvements in Flexible Braces, of which the following is a specification.

The purpose of the invention is to provide a brace for all sorts of vehicle apparatus whereby an appropriate connection may be made between the body and axles of a vehicle so that the vehicle springs may be relieved from lateral strains or from strains tending to distort them, such as is the case 15 when the axles are subject to sudden and acute shocks tending to move the axles laterally in the direction in the length of the vehicle body or frame.

A further purpose of the invention is to 20 provide means for more uniform distributing upon the axles the load carried by the vehicle body.

Other and further purposes of the invention appear hereinafter as the invention is 25 set forth in detail.

As shown and described a specific embodiment has been adhered to but to this embodiment the invention is not to be restricted. The right is reserved to make such changes 30 or alterations as the actual reduction to practice may suggest, in so far as such changes or alterations are compatible with the spirit of the annexed claims.

In the accompanying drawings:

35 Figure 1 is a top plan view of a portion of a vehicle frame and its attendant axle, the improved brace being shown applied thereto.

Fig. 2 is a section on the line 2—2 of 40 Fig. 1.

Fig. 3 is a perspective view of one of the brace elements.

Fig. 4 is a perspective view of the other 45 of the brace elements.

As illustrated, the invention is shown applied to a vehicular apparatus having the frame 1 and the axle 2. Pivotaly mounted on top of the axle adjacent the wheel 3 there is a rocker arm 4, while attached to 50 the corner of frame 1 there is a bracket 5 at an intermediate point in the length of the frame but on the side there is attached a bracket 6. Brace rods 7 and 8 connect the brackets 6 and 5 with the rocker arm 4, ball and socket (or link) joints 9 serving as 55 means of connection between the brace rods

and the brackets and similar ball and socket (or link) joints 10 serving as means of connection between the brace rods and the rocker arm 4.

60 The elements just described constitute one of the flexible bracing elements and in a great number of instances this element will be all that is required. The vehicle on which the invention is presumed to be attached is of the character designed for heavy service. Therefore, the second brace element is used in combination with the first. This second brace element comprises a rocker arm 11 pivotally mounted at its longitudinal 70 center on top of the axle 2 between the rocker arm 4 and the side longitudinal rail of the frame 1. Directly above this rocker arm 11, there is attached to the longitudinal rail of the frame a bracket 12 formed with 75 two downwardly directed diverging arms 14. Brace rods 15 connect these arms 14 with the rocker arm 11 and for these means of connection ball and socket (or link) joints 16 are employed.

80 On certain kinds of vehicles it may be preferable to use the brace element comprising the bracket 12 and its attendant parts, just as brace element comprising the rocker arm 4 and its attendant parts are 85 used on certain other kinds of vehicles both serving a similar purpose, but where additional bracing is desired the two may be used in conjunction, the difference in construction in the two providing for their 90 application in common to a vehicle on which it is desired to use them.

95 It is obvious that the construction of the bracing element provides for the oscillation of the frame of a vehicle on its axle but securely braces the latter against the frame when subject to shocks tending to move them laterally in the direction of the length of the frame. For example let it be supposed that the axle 2 is subject to a sudden shock 100 tending to move it laterally toward the bracket 6. This means that a strain will be imposed upon the brace rod 8 and that end of the rocker arm 4 with which the brace rod 8 is connected will be subject to a force 105 tending to move it toward the bracket 5, thus imposing a crushing strain on the brace rod 8, since the pivotal point of the rocker arm 4 will move in the direction in which the axle moves which is in the direction of the 110 bracket 6. But the force tending to move that end of the rocker arm 4 with which

the brace rod 8 is connected in the direction of the bracket 5 must perform tend to move the opposite end of the rocker arm in the opposite direction with the result that 5 the brace rod 7 is subject to a crushing strain. Thus the two brace rods coöperate to take care of the strain imposed upon the axle 2 tending to move it in the direction above assumed. A strain imposed upon the 10 axle in the opposite direction is, of course, taken care of in same way.

While differently constructed, of course the brace element comprising the bracket 12 and its attendant parts operates in essentially the same way to take care of lateral strains or shocks imposed upon the axle.

Just as the improved brace serves as a means for securing the axle against sudden shocks, so does it serve to uniformly distribute 20 to the axle the load carried by the frame. For example if a massive load is carried by the frame in the vicinity of the bracket 5, this strain is imparted to the frame in the vicinity of the bracket 6 through 25 the medium of the bracing rods 7 and 8 and the rocker arm 4, for as long as the frame does not vibrate on the springs,

the force creating the excessive strain at the bracket 5 is transferred to that part of the frame at which the bracket 6 is located. 30

The invention having been described, what is claimed as new and useful is:

In a brace for the purpose specified, the combination with the frame and axle of a vehicle, of a rocker arm pivotally mounted 35 on the axle at a point intermediate in the length of the arm, the said rocker arm being transversely disposed with reference to the axle, a bracket attached to the vehicle frame, the said bracket being formed with downwardly directed diverging arms disposed one substantially directly above each end of the rocker arm, and a pair of brace rods having universal connections both with the arms of the bracket and with the ends of the 40 rocker arm, the said rods being diagonally disposed and having their one end connected with the bracket arm diagonally opposite that end of the rocker arm with which their 45 other end connects. 50

In testimony whereof I affix my signature.

GEORGE W. SMITH.
